UNITED STATES PATENT OFFICE.

ERVIN E. STRAWN, OF DES MOINES, IOWA, ASSIGNOR TO THE OMNIGRAPH COMPANY,
OF DES MOINES, IOWA, A CORPORATION.

COMBINATION PRINTING, ADDRESSING, SCORING, AND CUTTING MACHINE.

1,414,054.

Specification of Letters Patent. Patented Apr. 25, 1922.

Application filed October 28, 1919. Serial No. 334,075.

To all whom it may concern:

Be it known that I, ERVIN E. STRAWN, a citizen of the United States, and a resident of Des Moines, in the county of Polk and State of Iowa, have invented a certain new and useful Combination Printing, Addressing, Scoring, and Cutting Machine, of which the following is a specification.

My invention relates to machines for printing, addressing, scoring and cutting paper whereby there may be completed an envelope, with return card printed in a suitable place by direct inking process, also name and address printed at proper place printed through ribbon to give perfect typewriter effect.

More particularly it is my object to provide a machine which will print on a moving paper strip or web, on certain sections of the paper, a return address by a direct inking process and will print in a suitable place an address through a ribbon, giving a perfect imitation of a typewritten address, and will then score the paper on certain lines adapted for folding and completing an envelope, and will then cut the paper in proper sizes for making a complete envelope.

Still a further object is to provide such a machine adapted for printing form letters on standard size sheets, and for intermittently advancing the paper the length of such a sheet, and for cutting the paper into such sheets, which machine has means adapted to cut and score envelopes as stated in connection with the regular paper advancing mechanism. Proper envelopes require a little less paper than the paper of such a letter sheet and in my machine I have provided means for making an ordinary check, receipt or the like out of the waste paper of each sheet in addition to the envelopes.

With these and other objects in view my invention consists in the construction, arrangement and combination of the various parts of the device, whereby the objects contemplated are attained, as hereinafter more fully set forth, pointed out in my claims and illustrated in the accompanying drawings, in which:

Figure 1 shows a side elevation of my improved machine.

Figure 2 shows a top or plan view of the envelope scoring and cutting device.

Figure 3 shows a vertical, sectional view taken on the line 3-3 of Figure 2.

Figure 4 shows a transverse, vertical, sectional view taken on the line 4-4 of Figure 2.

Figure 5 shows a perspective view of part of the envelope cutting and scoring mechanism.

Figure 6 shows a perspective sectional view of part of the cutting and scoring mechanism.

Figure 7 shows a perspective, sectional view through one of the printing rollers.

Figure 8 shows a plan view of the paper showing the line on which the envelope is scored and cut.

Figure 9 shows a detail view of one of the gearing devices, and

Figure 10 shows a vertical, transverse, sectional view through the same.

The portion of my machine which prints the return address and the addresses is similar to the machine shown in my application for patent Serial Number 182,165, filed July 23, 1917, to which application reference is made for a more complete description for these portions of the machine.

I will first describe in a general way the part of the machine which prints the address and the return address.

My machine includes the main or supporting frame, 10, shown in my hereinbefore identified application, of suitable size and shape and having suitable members for properly supporting the mechanism herein-after referred to.

Mounted on the frame 10 near what I shall call the forward end thereof is a prime mover such, for instance, as the electric motor 11 having a motor shaft 12, which is operatively connected by suitable mechanism with a transverse shaft 16.

Above the shaft 16 is a shaft 21 which is operatively connected with the shaft 16 by any suitable mechanism such, for instance, as that illustrated in my prior application, 100 which is not here further shown.

On the shaft 21 is a gear 22 which meshes with a gear 23 on the third shaft 24.

The frame 10 supports other transverse

shafts 27 and 28 which are operatively connected with each other and with the shaft 21 by suitable mechanism, such as is shown in my prior application, not here shown.

5 On the shaft 28 is a gear 29 which meshes with a gear 30 on a shaft 31, which shaft 31 is the main drive shaft for the address plate handling mechanism.

My improved machine has gearing devices 10 32, 33, 34 and 35 of the type shown in my prior application Serial Number 182,165, filed July 23, 1917, for operating printing mechanism and intermittently advancing the paper such as is shown in such prior application.

15 The gear 35 is connected by gearing devices 35^a, 35^b, 35^c, 35^d, 35^e, and 35^f with rollers 35^g and 35^h for advancing the paper 35ⁱ from the roll A. The gearing device 35^d is 20 operatively connected with printing roller shafts 35^j and 35^k as by a gearing device 35^l. The gearing device 35^l is connected by gearing devices 35^m and 35ⁿ with a cutter roller on shafts 35° and 35^p such as are shown in 25 my co-pending application Serial Number 182,165, filed July 23, 1917.

On the upper forward part of the supporting frame is a track comprising laterally spaced outwardly opened channel-shaped members 36 on which travels a carriage comprising the side members 37 connected by suitable cross members 37^a and having flanges 37^b received in said channel-shaped track members.

35 The carriage is adapted to reciprocate backward and forward in the machine and supports the printing roller or platen 37^c which is mounted on a shaft 37^d. The printing roller 37^c has journals 37^e, and the shaft 40 has enlarged portions 37^f received in said journals. The portions 37^f are arranged eccentric with relation to the body of the shaft 37^d.

The roller or platen 37^c is provided at 45 one end with a toothed gear 37^g. The ends of the shaft 37^d are mounted in the side members 37 of the carriage, and on one end of the shaft 37^d outside the carriage is a segmental gear 37^h which serves the purpose, hereinafter more fully explained, of 50 rotating the roller during certain portions of the operation of the parts of the machine for rotating the shaft portions 37^f in the journals 37^e for raising and lowering the roller.

55 Mounted in one of the side members 37 of the carriage, below the shaft 37^d is a stub shaft 37ⁱ on which is mounted a segmental gear 37^j which meshes with a segmental gear 37^h.

On the segmental gear 37^j is a downwardly extending arm 37^k. On the frame of the machine at points near the opposite limits of reciprocating movement of the platen

65 roller carriage are stop lugs 37^l and 37^m, the former being located near the forward end of the machine and the latter near the middle of the machine in such positions as to engage the arm 37^k when the carriage is near its respective limits of movement.

70

When the carriage moves toward the forward part of the machine the arm 37^k engages the lug 37^l for rotating the shaft 37^d for lowering the roller, and when the arm 37^k strikes the lug 37^m, the shaft 37^d is rotated for raising the roller 37^c.

75

The carriage is operated by means of a link 39 pivoted to one of the end members 37.

A lever 40 is pivoted at its lower end to the main frame of the machine and at its 80 upper end to the link 39.

On the shaft 21 is fixed an arm 42 to which is pivoted a pitman 41. The pitman extends forwardly in the machine and is pivoted at its forward end to the lever 40 85 between the ends thereof.

When the shaft 21 rotates, the pitman 41 is reciprocated for actuating the lever 40, thereby imparting reciprocating movement to the platen roller carriage.

90

Suitably supported, as for instance, in my prior application, are feeding and receiving magazines 45 and 46 for address plates.

It will be understood that the main frame 95 supports a chase for a type form near the rearward limit of movement of the carriage above described, and that suitable mechanism is provided for bringing the address plates to printing position at the proper time.

It will be noted that in the machine just described, there is mechanism for intermittently advancing paper.

This is a standard machine which I am 105 now manufacturing and can be used for printing form letters and the like.

It is my purpose to provide in connection with this machine a certain mechanism whereby the same machine can be used for 110 scoring and cutting envelopes.

The machine is ordinarily geared for advancing the paper intermittently a distance equal to the length of an ordinary letter.

I have found that an envelope can be made 115 with a shorter length of paper and have, therefore, provided herein means for scoring and printing a check adjacent to each envelope and the envelope and the check together are of the length of one ordinary letter sheet.

It will, of course, be understood that a receipt might be printed instead of a check.

Supported on the main frame of the machine and arranged to mesh with the gear 125 37^g is a rack 48, which is held in position by means of screws 47.

Supported on the frame 10 underneath

the path of travel of the roller platen is a frame 50 which supports a lower cutting member of a paper die.

5 Mounted at the side edges of the frame 50 are the cutter members 51, the outer edges of which are arranged to cut the paper according to the pattern shown in Figure 8, and indicated by the reference numeral 52.

10 At the sides of the frame 50 are longitudinally arranged frame members 53, having the form of angle irons, provided at their ends with upwardly turned portions 54.

15 Mounted in the upwardly turned portions 54 are transverse shafts 55, which extend through horizontally elongated slots 56 in the main frame. (Fig. 2.)

20 The upper die or cutting member includes longitudinally arranged frame members 57 arranged just inside of the respective frame members 53 which are raised and lowered in the manner hereinafter described by the reciprocation of the members 53.

25 Mounted on the frame members 57 are outer upper cutting members 58, the inner edges of which are shaped to conform to the outline 52, shown in Figure 8, and are arranged to coact with the cutting edges of the cutter members 51. Connecting the members 58 on the opposite sides of the machine are transverse connecting bars 59.

30 Supported on the frame 50 are frame members 60 in which are grooves 62 and 63 corresponding to the scoring lines 64 and 65 illustrated in Figure 8. Reference will be made to the frame members 60 and 61 hereafter.

35 Supported on the frame members 59 are transverse members 66 having the downwardly projecting flanges 67 for scoring paper.

40 Supported on the members 59 are longitudinally arranged members 68 having the flanges 69 designed to serve as scoring members for scoring the lines 65.

45 The flanges 67 are arranged to coact with the grooves 62 and the flanges 69 are arranged to coact with the grooves 63 for scoring the respective lines 64 and 65.

50 The frame members 57 are supported on the frame members 53 by means of laterally extending pins 70 which project through inclined elongated slots 71 in the frame members 53.

55 Supported at the rear end of the frame 50 is a printer's chase 71 for receiving a chase for printing matter on the check or receipt form hereinbefore referred to. (Fig. 6.)

60 Mounted on the frame 50 is a longitudinally arranged bar 72 having formed there-

65 in a groove 73. (Fig. 2.)

65 Formed on the frame members 57 at the

ends thereof, are downwardly projecting legs 75 designed to travel in vertical grooves 76 in the frame 50 for holding the die or cutting member against longitudinal movement in the machine and for permitting vertical reciprocation thereof.

70 I will now explain the practical operation of my improved machine when used with the attachments for cutting and scoring envelopes and checks or receipts.

75 In a preliminary way I may say that Figure 8 shows a section of the paper 35 having outlined thereon an envelope indicated generally by the reference character B. At one end of the envelope is the outline of a check 80 or the like C having certain printed matter 76 thereon.

80 In the practical operation of my improved machine, when the motor is started it will be seen that reciprocatory movement will be imparted to the lever 40 for moving the printing platen backward and forward on the machine.

85 On account of the use of the pinion 37^c and the rack 48 it will be seen that the perforating strip 74 will always properly coact with the groove 73.

90 Assume that the roller platen is at the right-hand limit of its movement, as shown in Figure 1, then it will be slid forwardly 95 in the machine and the paper on the type in the chase in the form 71 will be printed.

95 The line 77 will be scored during such movement.

100 Just before the platen reaches its forward limit of movement, the engaging members 78 on the members 37 will engage the projecting ends of the forward ends of the shaft 55, and as result the frame members 53 will be slid forwardly in the machine thereby 105 causing the pins 70 to travel upwardly in the grooves 71 for raising the upper cutting member of the die.

110 At the finish of the forward movement of the roller, the arm 37^c strikes the lug 37^m 110 for actuating the segmental gear 37^e and the segmental gear 37^h for rotating the shaft 37^b for bringing the cam portion 37^t thereof to position for raising the roller.

115 On the first part of the rearward movement of the roller, the paper is advanced in the machine.

120 When the roller is near its rearward limit of movement, the arm 37^c strikes the lug 37^t for lowering the platen roller and during 120 the last part of the rearward movement of said roller, the engaging member 79 will strike the laterally projecting ends of the rearward shaft 55 for sliding the frame members 53 rearwardly, and thereby causing the pins 70 to travel downwardly in the slots 71 and cause the cutting edges of the die members 58 to coact with the cutting edges of the members 61 for cutting the paper on lines 52.

At the same time the downwardly projecting flanges 67 and 69 coact with the grooves 62 and 63 for forming the scored lines 64 and 65.

5 It will be understood that the cut off mechanism at the forward end of the machine, which would ordinarily cut the paper in letter size, will cut the paper along the lines 78^a and 80, and thereafter the receipt 10 or check may be severed from the envelope blank. The envelope may afterwards be folded as desired.

It will be seen that I have provided, in connection with a standard machine which 15 I am already manufacturing, an attachment which can be readily and easily mounted on the machine for cutting envelopes and preparing checks or receipts, while using the ordinary machine constructed in the ordinary way, and having mechanism for cutting the paper into sheets and for intermittently advancing it.

The use of such an attachment or additional parts makes it possible to greatly increase 25 the range of utility of my printing machine.

It may be noted that the ordinary printing mechanism of this machine can be used for printing return addresses or the like on 30 the envelope.

Some changes may be made in the construction and arrangement of the parts of my device without departing from the real purpose of my invention, and it is my intention 35 to cover by my claims any modified forms of structure or use of mechanical equivalents which may be reasonably included within their scope.

I claim as my invention:

40 1. A device of the class described adapted for use in a machine having means for intermittently advancing paper, including a die member, a coacting movable die member, a platen roller mounted for reciprocating movement, scoring means carried by said roller, and means adapted to be actuated by the movement of said platen for raising and lowering the movable die member.

45 2. A device of the class described adapted for use in a machine having means for advancing a strip of paper through the machine with an intermittent movement, including a die member, a coacting movable die member, a roller platen, scoring means carried thereby, means for advancing said roller over the strip of paper, and means for moving said roller away from the paper and returning it.

50 3. In a device of the class described designed for use in a machine having means for advancing paper through the machine, a die member, a coacting movable die member, a printing bed, a platen roller for coacting with said printing bed, means for 55 moving said roller over said paper and per-

manent bed, and means actuated by the movement of said platen for operating said movable die member.

4. In a device of the class described designed for use in a machine having means 70 for advancing paper through the machine, a die member, a coacting movable die member, a printing bed, a platen roller for coacting with said printing bed, means for moving said roller over said paper and permanent bed, and means actuated by the movement of said platen for operating said movable die member, and scoring means carried by said roller.

5. In a device of the class described designed for use with a machine having means 80 for advancing paper through the machine, a die member, a coacting movable die member, a printing bed, a platen roller for coacting with said printing bed, means for moving said roller over said paper and permanent bed, and means actuated by the movement of said platen for operating said movable die member, said machine having means for moving said platen away from said paper and returning it to its starting position.

6. In a device of the class described designed for use with a machine having means for advancing paper through said machine with an intermittent movement, means for 95 scoring and means for cutting on each predetermined length of said paper an envelope and a check or the like.

7. In a device of the class described designed for use with a machine having means 100 for advancing paper through the machine with an intermittent movement, a fixed die, a movable die for coacting therewith for scoring and cutting envelopes, a printing base adjacent to said fixed die, a roller platen adapted to be reciprocated over the paper above said bed, means on said roller platen for scoring that portion of the paper adjacent to the bed, and means adapted to be actuated by the movement of said roller 105 platen for operating said movable die.

8. In a device of the class described designed for use with a machine having means for intermittently advancing paper through the machine, means for cutting and means 115 for scoring on each predetermined length of paper and envelope and means for scoring on a portion of said predetermined length a check or the like.

9. In a device of the class described designed for use with a machine having means for intermittently advancing paper through the machine, means for cutting and means for scoring on each predetermined length of paper an envelope and means for scoring on 120 a portion of said predetermined length a check or the like and for printing said check or the like.

10. In a device of the class described designed for use with a machine having means 130

for intermittently moving paper through the machine, mechanism whereby between successive movements there is scored and means whereby there is cut on each predetermined length of paper an envelope, beside which there is scored and cut a check or the like.

5 11. In a device of the class described designed for use with a machine having means for intermittently moving paper through the

machine, mechanism whereby between successive movements there is scored and means whereby there is cut on each predetermined length of paper an envelope, beside which there is scored, cut, and printed a check or the like.

Des Moines, Iowa, June 30, 1919.

ERVIN E. STRAWN.
